RING CIRCUITS

Arthur B. Moulton, San Diego, Calif.

Application April 6, 1954, Serial No. 421,461

2 Claims. (Cl. 315—84.5)

(Granted under Title 35, U. S. Code (1952), sec. 266)

This invention is in ring circuits and specifically is a simple ring circuit utilizing gas-filled tubes only.

One object of the invention is to provide a ring circuit comprising one gas-filled tube for each stage.

Another object of the invention is to provide a ring circuit of the nature mentioned requiring no negative bias source such as is usually required.

Other objects will be apparent from a reading of the following specification and claims.

The drawing is a schematic diagram of a ring circuit according to my invention.

In the drawing, 10, 11, and 12 are three gas-filled ring tubes. It will be understood, of course, that the ring may contain as many tubes as desired and that to complete the ring circuit connections must be made between points X and X¹ on the one hand and Y and Y¹ on the other.

The nature of the circuit will be thoroughly understood, it is believed, from a description of its operation. Assuming heater voltage to have been applied in conventional fashion, and plate voltage applied, all tubes are biased in like fashion by the currents flowing through resistors 20, 21, and 22 (tube 10) and the corresponding elements for the other stages, 23, 24, 25 (tube 11), and 26, 27, 28 (tube 12). Values for these resistors are selected (in a manner to be explained) so as normally to prevent tubes 10, 11, and 12 from conducting. Switch 35 is provided for lowering the bias of tube 10 to zero (when closed) so that the ring circuit can be started.

When tube 10 conducts, its plate potential falls, and a small negative pulse is applied to the plates of the other tubes, but, since none of these is conducting, the pulse may be disregarded. As a result, however, of conduction in tube 10, the cathode-to-ground potential of tube 11 is lowered, and the tube, therefore, will conduct more readily than the other tubes in the ring. Tube 12 is not similarly affected.

A condition of imbalance now exists in the circuit such that if a positive trigger pulse is applied to the grids of all tubes, over line 40, and the several resistance-capacitance circuits as 41, 42, tube 11 will conduct, tube 10 will be extinguished by means of a voltage pulse coupled back to the plate of tube 10 through condenser 45, and the remaining tubes of the ring will not be affected; resistor 50 prevents changes in the grid voltage of tube 11 from disturbing the other tubes in the circuit. Thereafter, each time a triggering pulse is applied a different tube will conduct and the previously conducting tube will cease conducting. The order of stepping (in the embodiment shown) is 10, 11, 12, . . . 10, etc.

The proper operation of the circuit depends upon the selection of correct values for resistors 20, 21, and 22 and the corresponding elements for the other stages. The following conditions must be met: the plate voltages of the conducting tube and the succeeding (primed) tube must be so related that, when the latter starts to conduct, sufficient voltage will be coupled back to the plate of the former to extinguish the same; the cathode bias

2

provided by resistors 20, 23, and 26 must be sufficient to keep all but one tube from conducting; there must be enough difference between the currents i_2 and i_3 (when tube 10 is conducting, for example) that the primed tube 11 may be more easily triggered than any other tube.

The resistor values can be determined by trial and error but calculation also is possible according to the following formulas:

$$i_1 = \frac{E_p \left(\frac{1-R_2}{R_1+R_2+R_3} \right) \left(\frac{1+R_2}{R_2+R_3} \right) - V}{R_1+R_2+\frac{R_1R_3}{R_2+R_3} - \frac{R_2^2 \left(1+\frac{R_1}{R_2+R_3} \right)}{R_1+R_2+R_3}}$$

$$i_2 = \frac{E_p - i_1 R_1}{R_2+R_3}$$

$$i_3 = \frac{E_p}{R_1+R_2+R_3}$$

$$i_4 = \frac{E_p \left(1 + \frac{R_2}{R_2+R_3} \right) - R_2 i_1 \left(1 + \frac{R_1}{R_2+R_3} \right)}{R_1+R_2+R_3}$$

25 R₁, R₂ and R₃ are the resistors 22, 20, and 21 respectively (and analogous components), and i₁, i₂, i₃, and i₄ are the currents shown on the drawing; E_p is the plate supply voltage, and V is the voltage drop across a tube when it is conducting.

30 According to one embodiment of the invention, circuit elements and supply voltages are:

Tubes ----- 884 thyratrons.

Resistors:

35 41, 61, 81	22,000 ohms.
21, 22, 24, 25, 27, 28	47,000 ohms.
20, 23, 26	15,000 ohms.
50, 51, 52	100,000 ohms.

Condensers:

40 45, 46, 47	0.3 microfarad.
42, 62, 82	.0062 microfarad.

B+ ----- 240 volts.

45 The foregoing description is in specific terms, and many modifications will suggest themselves, so that for the true scope of the invention reference should be had to the appended claims.

I claim:

50 1. A ring circuit including a succession of gas filled triodes each comprising a plate, a grid, and a cathode, a separate plate resistor for each tube, a separate cathode resistor for each tube, a source of voltage including a positive terminal and a negative terminal and a plurality of circuits each including the cathode resistor for one tube, the plate resistor for the preceding tube, and a further resistor intermediate the same, a capacitative coupling between the plate of each tube and the plate of its preceding tube, and means for applying triggering pulses simultaneously to the grids of said tubes, the values of the voltage source and the said resistors being so related as to permit conduction in but one tube at one time, so as to promote successive conduction in selected tubes, and so as to provide sufficient voltage at initiation of conduction in a tube to extinguish a preceding tube.

55 2. A ring circuit including a succession of gas filled triodes each comprising a plate, a grid, and a cathode, a separate plate resistor for each tube, a separate cathode resistor for each tube, a source of positive voltage, a source of negative voltage and a plurality of circuits each including the cathode resistor for a different one of said tubes, the plate resistor for the preceding tube, and a further resistor intermediate the same, a capacitative coupling between the plate of each tube and the plate of its

preceding tube, and means for applying triggering pulses simultaneously to the grids of said tubes, the values of the voltage sources and the said resistors being so related as to permit conduction in but one tube at one time, so as to promote successive conduction in selected tubes, and so as to provide sufficient voltage at initiation of conduction in a tube to extinguish a preceding tube.
